Inventor
By Frank S. Ackerman.

Attorney

UNITED STATES PATENT OFFICE.

WILLIAM F. RAMIGE, OF ROCKWELL CITY, IOWA.

TRACE CARRIER.

Application filed June 21, 1922. Serial No. 569,977.

To all whom it may concern:

Be it known that I, WILLIAM F. RAMIGE, a citizen of the United States of America, and resident of Rockwell City, in the county 5 of Calhoun and State of Iowa, have invented certain new and useful Improvements in Trace Carriers, of which the following is a specification.

This invention relates to certain improvements in trace carriers, and has for an object 10 to provide means for connecting the back and hip straps of harness with a hook for engagement with the end or cock eye of a trace, there being present, means or closing 15 the upper end of the hook when sustained thereby.

A trace carrier made in accordance with one embodiment of my invention comprises a frame, which has the usual side and end 20 loops for the back and hip straps of harness, and such frame is integral with a frame that occupies a position which locates the latter frame in a higher position than the one which is provided for the harness straps 25 other than the trace, such frame having guards and between the guards a hook or hooks, with which the cock eye or eyes of a trace or harness may be placed in engagement and so held.

The invention also comprises a back band 30 loop or frame which maintains at a different elevation or plane, a trace carrying structure having means with which a cock eye or ring may engage, and in addition thereto, a resilient member for closing the 35 open end of the cock eye or trace carrier, there also being present, guards for the hooks.

My invention further consists in the 40 make-up of a frame or back band loop which is formed integral with a frame having trace carrier hooks, which frame carries a spring mounted on a rockable fulcrum and located between guards which form a part 45 of the last mentioned frame.

My invention further consists in a trace 50 carrier having a hook or hooks, a spring for engagement with a hook or hooks, the spring and hook or hooks both being maintained above the plane of the back band loop, there

also being present, side guards for the spring and trace carrier hook or hooks.

In the accompanying drawings—

Figure 1 illustrates a perspective view of a trace carrier made in accordance with my 55 invention;

Figure 2 illustrates a section taken to one side of the longitudinal center of the device, in which illustration a pad is shown, associated with the back straps;

Figure 3 illustrates a plan view;

Figure 4 illustrates a transverse section; and

Figure 5 illustrates a perspective view of a preferred form of a modification of my 65 invention.

Referring to the drawings, 10 indicates the frame to which the usual back and hip straps of a harness are attached. This frame 10 and a hook and guard frame 11 70 are integral, being connected by members 12 which stand upward and incline inward from the frame 10, such connecting means also being integral with a substantially rectangular frame 13 and guide bars 14 which 75 are arched, and at an intermediate point the side bars of the frame 11 have upward projecting portions with centrally located recesses to receive the ends or gudgeons that project from a rocking member 15 or cross 80 bar that is centrally apertured, to receive a flat spring 16 which may be permanently secured to the rocking bar by a connecting pin 17 or other appropriate device.

The frame, in addition to the guards, carries hooks 18 and the ends of said springs 85 extending inward and being engaged by the free ends of the spring.

It will be readily understood from the drawings that the spring, the supporting 90 frame, the hooks and the guards are maintained above the plane of the base portion, and provide means whereby the spring may be moved to receive the larger wearing portion of the usual cock eye attached to traces, 95 and that the side guards prevent any entanglement of straps or driving reins with the structure in use.

In Figure 5, I have shown a modified 100 form of my invention which is adapted for

use as a hip strap trace carrier, the spring, in such instance, being maintained upon a rocking support, and the upper frame having an apertured projection 19 to receive 5 one end of the spring.

From the foregoing description, it will be noted that the trace carrier or trace end supporter is made up of one piece and comprises an elliptically shaped frame with 10 members that carry a substantially rectangular frame, the longitudinal bars thereof having arched rein guards and upstanding lugs with recesses, the transverse bars of the frame having hooks with inward and 15 downward open ends. The keeper spring for the hooks is associated with a bar which is centrally apertured for the passage of a flat spring, of a length sufficient to engage with and extend beyond the ends of the 20 hooks. The ends of the spring may be depressed by the cock eye of the trace to position the ends of the spring to admit the cock eye below the hook, and when in place, the spring holds the cock eye from displacement; as the end of the spring is depressed, 25 the cross bar which carries the same, will be rocked and tension thereon will be distributed, and only a flat unbent spring is required for both hooks.

30 In Fig. 5, which is designed as an attach-

ment for hip straps, there is a single hook and an upstanding part on the cross bar, the bearing lugs being on the longitudinal upper bars adjacent to the ends of the rein guards.

35

I claim:

1. A trace carrier comprising a frame having recessed lugs, a transverse bar, the ends of which are seated between the lugs, a flat spring maintained by the bar, and hooks integral with the frame, the ends of 40 said hooks engaging opposite end portions of the spring.

2. A trace carrier comprising a base frame having within its perimeter a pair of upstanding guards, integral transverse members having inward extending hooks, the end portions thereof terminating above the plane of said transverse members, a cross bar centrally positioned and maintained 45 above the plane of the base frame, a flat spring of greater length than the distance between the ends of the hooks, said spring being attached to the cross bar to position its ends beyond the inward extending ends 50 of the hooks, the parts, excepting the spring and cross bar to which the spring is attached, being integral.
